(57) CLAIM

The ornamental design for a bottle, as shown and described.

DESCRIPTION

FIG. 1 is a perspective view of a bottle showing our new
design;

FIG. 2 is a side elevational view thereof, the design being
continuous for 360° around the bottle;

FIG. 3 is a bottom plan view thereof; and,

FIG. 4 is a top plan view thereof.

Throughout the figures lines shown in phantom are for
illustrative purposes only and form no part of the claimed
design.
